CHARLES B. BELKNAP, OF HIGHLAND PARK, MICHIGAN.

MEANS FOR TREATING OILS.

Continuation of application Serial No. 413,758, filed September 30, 1920. This application filed May 7, 1925, Serial No. 28,725. Renewed July 25, 1928.

My invention relates to improvements in means for treating oils and more particularly to an apparatus for treating hydrocarbons and the like.

5 Among the salient objects of the invention are to provide a means for treating oils in which the entire space in the apparatus is initially filled with oil under a mechanical pressure as high as that desired in the treatment of the oil; to provide an apparatus for treating hydrocarbons and other oils in which the vapors are prevented from coming off except at the temperature and pressure desired; to provide an improved means for treating 10 oils in which the vapors generated will not produce any higher pressure in the apparatus than that produced by the mechanical pressure; to provide an improved means and apparatus for treating oils in which the pressure maintained on both the oil and the vapor is always a mechanical pressure and under control of the operator; to provide an improved means for treating oils in which the vapor space can automatically increase as the 15 vapors increase and in which the vapors are prevented from passing out of the still until the level of the oil is forced back to a predetermined level; and in general to provide an improved means for treating oils in which the vapor space, pressure and temperature 20 can each be regulated independent of the others.

In the drawings:

Fig. 1 is a side elevation, partly in section, through an apparatus embodying my invention.

Fig. 2 is a cross section on the line 2—2 of Fig. 1.

Referring to the apparatus shown in the drawings and describing in detail the apparatus, 1 designates a still or retort formed of headers 2 and 3 connected by a plurality of vertically extending pipes 4. The latter pass through the flue chamber of a furnace 5, which is provided with fire-box 6 and stack 7. The hot gases in passing from the fire-box to the stack are compelled to pass around the end 8 of the horizontal baffle 9 through which the pipes 4 extend, thus heating the latter.

Oil is supplied to the header 3 by means of a conduit 10 connecting to a force pump 11, which is adapted to draw oil from any suitable source of supply through the inlet 12. Positioned between the pump and the header 3 is a check valve 13 which will prevent the

return through the conduit 10 of any oil pumped into the header. Leading from any suitable part of the still apparatus and preferably from the lower header is a discharge conduit 14 provided with a weighted valve 15, the purpose of this valve being to permit the oil to flow back out of the header 3 whenever the pressure in the still apparatus exceeds that at which the valve 15 is set.

In starting the apparatus, oil is forced by means of the pump 11 through the conduit 10 into the header 3, vertical pipes 4 and header 2 until the apparatus is entirely filled, any air or other gas which may be in the still, being allowed to escape through the pet cock 16, after which the latter is closed. When the entire space in the still has been filled with oil, the pumping is continued and places the oil under an increasing pressure until such pressure is reached as will raise the loaded valve 15 and permit the oil to flow out of the return conduit 14. The fire in the furnace 5 having been started, the temperature of the oil is increased until it reaches a point where vapors will be generated at the pressure at which the oil in the still is maintained. As soon as any vapors are generated they would have a tendency to increase the pressure within the still but this is prevented by the action of the loaded valve 15, which permits the passage of oil through the return conduit 14, when the pressure in the still exceeds that at which the valve 15 is set. Thus in place of the vapors generated increasing the pressure, they automatically increase the vapor space and this increase of vapor space may be continued to any desired level in the still apparatus.

As shown in detail in Fig. 1, the passage of vapors which would naturally accumulate in the upper header is governed by a valve 17 actuated toward and from its seat by means of a motor 18. The control for the latter comprises a plurality of pairs of contacts 19 and 19', and 20 and 20', etc., the connection between which is closed by a contact plate 21 carried by a stem 22, the lower end of which is provided with a float 23. This float is preferably mounted in a pipe 24, positioned outside the furnace, and connected to the headers 2 and 3 by means of conduits 26 and 27. The construction of parts is such that the headers 2 and 3, the vertical pipes 4 and the pipe 24 are all in open communication.

The upper set of contacts such as 19 and 19' 110

are arranged in a circuit, which, when closed will drive the motor in a direction to adjust the valve 17 against its seat. The other set of contacts 20 and 20', are arranged in a reverse circuit, that is, one which when closed will drive the motor in a direction to move the valve 17 away from its seat 25. As the vapors generate and force the level of the oil in the still back, they will finally reach a level 10 at which the float 23 will move down by gravity sufficient to bring its contact 21 into registration with the contacts 20 and 20'. When the reverse circuit is thus closed the motor 18, acting through the gears 28 and 29, will with- 15 draw the valve 17 from its seat and permit the vapors to escape into the inclined pipe 30, from which they are discharged into the condenser 31. A loaded valve 32 may be em- 20 ployed on the discharge end of the condenser, if it is desired to condense the vapors under substantially the same pressure at which they are generated, the valve 32 being set at sub- 25 stantially the same but slightly less pressure than the valve 15. In starting the apparatus 30 the condenser may be filled with distillate at a pressure substantially as great as that at which the loaded valve 32 is set so that all the vapors may be both generated and condensed under substantially the same pressure. 35 Whenever sufficient vapors escape past the valve 17 so as to tend to reduce the pressure in the still, the constant mechanical pressure on oil will raise the level of the oil and by raising the float and the contact 21 will close the cir- 40 cuit controlled by the contacts 19 and 19', and actuate the motor in its forward direction to close the valve 17 to its seat.

It is obvious that by changing the levels of the contacts 20 and 20' in the pipe 24, the 45 maximum amount of vapor space can be increased or decreased, or if desired, a plurality of sets of reverse contacts 20 and 20' could be employed and governed by a switch so that the operator could at his will adjust the maximum vapor space in the apparatus.

From the above description, it is obvious that the pressure in the still is at all times governed by the pressure at which the loaded valve 15 in the return conduit 14 is set and 50 that the vapors generated cannot increase or decrease the pressure. Moreover, since the pressure on the still is always a mechanical pressure it can be changed at the will of the operator by adjusting the weight 33 on the 55 loaded valve 15. As the temperature can be governed by the fires in the furnace 5 and the maximum vapor space is governed by the position of the contact 20 and 20', it is obvious that the pressure, temperature, and vapor can 60 be adjusted each independent of the other, although to generate vapors, it is, of course, necessary to have the temperature sufficiently high to drive off the vapors from the substance treated at the mechanical pressure em- 65 ployed.

My apparatus is therefore capable of carrying out a method of treating oils such as in the manufacture of gasoline, in which the distillate is vaporized at a constant pressure and in which none of the vapors can come off at 70 less than the pressure desired. Also my apparatus is capable of a method in which the vapor space automatically increases to the desired maximum without increasing the pressure, thus allowing the vapors to be super- 75 heated without danger of explosion such as is present where the oil or vapor is heated and the pressure governed by the temperature.

It will be noticed that the vertical extending pipes are the only portion of the apparatus which extend through the furnace, and where high temperatures and pressures are employed, the danger of subjecting a large body of oil directly to the action of the heat is avoided. Also the employment of the vertical 80 pipes in connection with the headers allows the apparatus to be cleaned and for this purpose I have shown a hand hole fitting for each header as indicated at 34 and 35. Where ex- 85 tremely high temperatures and pressures are 90 employed, the size of the headers might be re- 95 duced and a single row of vertical tubes con- nected into a pipe at each end to be employed.

While I have shown and described one form 100 of apparatus capable of carrying out my 95 method of treating oils, it is obvious that other apparatus could be employed such as a bell tank, similar to those used in commercial gas production, or various other forms of apparatus.

This application is a continuation of an 105 application formerly filed by me, Serial No. 413,753 filed September 30th, 1920.

I claim as my invention:

1. An apparatus for treating oils, the combination with means for mechanically placing the oil, while in a liquid state under a pre-determined pressure, means for heating the oil while in a liquid state, said first means being arranged to prevent the generation of 110 vapors until after the oil has been heated in a liquid state under a pre-determined pres- 115 sure and means thereafter for providing a vapor space adjacent the oil in the liquid state, to receive the vapors generated.

2. In an apparatus for treating oils, the combination with a still, of a pump for supplying oil to the still under pressure, a connection for the discharge of liquid and a loaded valve in said connection for preventing 120 excessive pressure, a valve outlet for egress of vapors, and a float for controlling the egress of vapors through said valve outlet when sufficient oil has been forced past the loaded valve to cover the float to a pre- 125 determined level.

3. In an oil-treating apparatus the combination with a still, of means for feeding oil thereto under pressure, a vapor outlet from the still, means acting automatically in re- 130

sponse to the level of oil in said still for permitting the escape of vapors from the still when the oil reaches a pre-determined level therein.

5. 4. The combination with an oil still, means for feeding oil therein under pressure, said still having a vapor space, a vapor discharge,

a valve controlling said discharge and automatically acting means responsive to the level of the oil in the still for actuating said valve 10 to open and close the same during the conversion of oil in the still.

CHARLES B. BELKNAP.
